THREADLESS LAMP SOCKET

Thomas E. Carroll, Bronx, N. Y.

Application June 26, 1937, Serial No. 150,517

1 Claim. (Cl. 173—358)

This invention relates to improvements in electric lamp sockets and more particularly to threadless lamp sockets adapted to be used in conjunction with a standard electric lamp of the usual screw-threaded base construction.

One object of this invention is a socket for receiving and securely retaining the standard screw-threaded base of an electric lamp without the necessity of rotating either the socket or the lamp.

Another object is a socket adapted for the ready connection of electric appliances without rotation of the connecting plug associated with said appliance.

Another object is a lamp holder of simple construction and positive operation which can be manufactured at no additional cost to that of the usual threaded type of lamp holder employed in the socket assembly now in common use.

Another object is a lamp holder of the punched type as above mentioned made from a single piece of metal.

Other objects will appear from the detailed description.

In the drawing comprising but a single sheet of three figures numbered Figs. 1 to 3 inclusive,

Fig. 1 is an elevation of my improved socket assembly with a standard electric lamp engaged therewith, a portion of the assembly being broken away to show certain of the parts in section.

Fig. 2 is a perspective view of one form of my improved lamp holder, and

Fig. 3 is a perspective view of another form of my holder with a portion thereof broken away and shown in section.

Like reference characters designate corresponding parts throughout the several figures of the drawing.

Referring to Fig. 1, lamp 29 is provided with a standard screw-threaded base 30, adapted to be secured by rotation in the well-known manner in a standard screw-threaded socket assembly.

In lieu of said standard assembly however, I provide a socket assembly 10 including the usual outer metal shell 11, insulating sleeve 20, metal cap closure 12, insulating base 13, off-button 14, on-button 15, terminal strap 16, twin cable 17, and central contact 18.

An insulating washer 19 is placed between insulating base 13 and my improved lamp holder punching 21 (or 31, Fig. 3, which may be used as a substitute therefor).

Holder 21 consists of an annular hub 22, from which radiate a series of prongs including a plurality of spring fingers 23 alternating with a plurality of grip fingers 24.

Hub 22 and fingers 23 and 24 are all punched out from a single piece of metal, and the fingers 23 and 24 are thereafter bent substantially at right angles to the annular hub 22, so that hub 22 and fingers 23 and 24 in conjunction form the lamp holder 21.

Fingers 23 and 24 are resilient, and the tips of fingers 23 are inwardly curvedly bent at 25 to form spring contacts for engaging against the threaded grooves of screw base 30 of lamp 29. The fingers 24 are longitudinally corrugated or embossed to form inwardly extending longitudinal ribs 26 which press against spaced portions of the surface of screw base 30 to retain said screw base in fixed position. Annular hub 22 is provided with a plurality of openings 28 for receiving screw bolts (not shown) whereby lamp holder punching 21 is secured to insulating base 13 of socket assembly 10. The conjoint clamping action of spring contacts 25 of spring fingers 23, and of longitudinal ribs 26 of resilient grip fingers 24, tend to clamp and retain screw base 30 and consequently lamp 29 in fixed position in the socket assembly 10. Lamp 29 may be inserted and withdrawn from lamp holder 21 thus formed by a straight in and out movement without any turning or rotating of screw base 30.

The annular hub 22 of lamp holder 21 may be provided with a series of spacers 27 positioned between the several spring fingers 23 and resilient grip fingers 24 (see Fig. 2). These spacers when provided tend to space spring fingers 23 and grip fingers 24 away from the inner wall of insulating sleeve 20, thereby increasing the available outward travel of the finger tips when screw base 30 is inserted therein. The lamp holder 21 however will operate quite satisfactorily even when the spacers 27 are not employed.

The inwardly bent spring contacts 25 of the spring fingers 23 may either be so adjusted as to engage the bevelled side wall of the last threaded groove of screw base 30 of lamp 29 substantially as shown at the left in Fig. 1 which arrangement gives very satisfactory results, or the spring contacts 25 may if preferred be inwardly curvedly bent at an oblique angle conforming substantially to the pitch of the threaded grooves of screw base 30, to permit the spring contacts 25 to engage within the uppermost threaded groove of the screw base.

In the construction shown in Fig. 2 lamp holder 21 employs three spring fingers 23 alternating with three grip fingers 24, but lamp holder 21 may be provided merely with a plurality of spring fingers 23 alternating with a plurality of grip fingers 24.

5 fingers 24, or the grip fingers 24 may be omitted entirely with satisfactory results provided three or more spring fingers 23 having spring contacts 25 are employed to insure at least a three point contact.

10 Fig. 3 illustrates an alternative form of construction wherein the lamp holder punching 31 consists of a one-piece cylindrical shell 35 having one end bent inwards at right angles to form an inwardly projecting flange forming an annular hub 32 having a central opening 33. Hub 32 is provided with suitable openings 34 for receiving screw bolts whereby holder 31 is secured to insulating base 13.

15 16 A plurality of spring fingers 36 which may form an integral part of lamp holder punching 31 extend beyond the end of cylindrical shell 35. Fingers 36 are inwardly curvedly bent to form a plurality of spring contacts 37 adapted to engage 20 against the threaded wall of screw base 30.

25 Cylindrical shell 35 may be provided with a plurality of corrugations to form longitudinal ribs 38 corresponding substantially to the longitudinal ribs 26 of the grip fingers 24 of the lamp holder punching 21. Corrugations 38 if provided should be spaced substantially midway between the spring fingers 36. Lamp holder 31 is preferably provided with at least three of the spring fingers 36.

What is claimed is:

5 A socket for receiving and retaining a screw-threaded lamp base comprising a metal punching; said punching including a disc, a series of spaced prongs merging with the outer peripheral edge of said disc and in continuation thereof, and a series of spacers projecting laterally outwards from the peripheral edge of said disc between said prongs, the central opening in the disc being large enough to spacedly receive a 10 central contact electrically insulated from the disc and forming one electrode of the socket, said prongs being bent substantially at right angles to said disc at the line of merger therewith to form the other electrode for the socket and a 15 holding clamp for a lamp base, the stems of certain of the spaced prongs being longitudinally inwardly embossed to form corrugations or ribs for engaging along the surface of the lamp base transverse the screw threads at a plurality of spaced points, the tips of the other spaced prongs being inwardly curvedly bent to form spring contacts for engaging spaced arcs of a threaded lamp base, and the spacers projecting from said 20 disc between and beyond said prongs to retain them in spaced relation to the insulating shell of the socket.
